UNITED STATES PATENT OFFICE.

JOHN W. GRIDLEY, OF SOUTHBURY, CONNECTICUT, ASSIGNOR TO THE SOUTHBURY CUTLERY COMPANY, OF SAME PLACE.

DESIGN FOR A CURRY-COMB.

SPECIFICATION forming part of Design No. 14,572, dated January 29, 1884.

Application filed March 5, 1883. Term of patent 14 years.

To all whom it may concern:

Be it known that I, JOHN W. GRIDLEY, a citizen of the United States, residing at Southbury, in the county of Hartford and State of Connecticut, have invented and produced a new and original Design for a Curry-Comb, of which the following is a specification, reference being had to the accompanying drawing, forming part thereof.

10 Said drawing shows a perspective view of my newly-designed curry-comb.

Heretofore curry-combs have been made having frames whose contour, exclusive of the handle, was horseshoe-shaped when viewed in plan view; also, with straight parallel sides and rounded ends. Horse-brushes have also been made with solid backs of oval contour.

15 The leading features of my design consist of the oval contour for the comb-frame and of the curved braces which connect the two sides of the frame.

20 A designates the oval frame; B B, the curved braces, extending transversely across the frame, with their convex edges confronting each other. C designates the shank, to which any ordinary handle, D, is secured. E designates

ordinary comb-bars, preferably extending the longest way of the oval-shaped frame; and a a designate projections at the ends of the frame. While I prefer to provide the frame with said projections a a, they may be omitted without changing the other features of my design. 30

My oval frame differs from a solid back of oval contour, because it contains an oval opening. In other words, it is literally in the 35 form of a frame, and its internal, as well as its external, contour I make of an oval form.

I claim—

1. The design for a curry-comb herein shown and described, the same consisting of the frame 40 having an oval contour both internally and externally.

2. The design for a curry-comb herein shown and described, the same consisting of the frame having an oval contour and the curved transverse braces, with their edges confronting each other. 45

JOHN W. GRIDLEY.
